UNITED STATES PATENT OFFICE.

AUGUST J. PETRIE, OF WEST ALLIS, WISCONSIN, ASSIGNOR TO MILWAUKEE STAMPING COMPANY, OF WEST ALLIS, WISCONSIN.

BAG-FRAME BRACKET.

Application filed November 26, 1923. Serial No. 676,921.

To all whom it may concern:

Be it known that I, AUGUST J. PETRIE, a citizen of the United States, residing at West Allis, county of Milwaukee, and State of Wisconsin, have invented new and useful Improvements in Bag-Frame Brackets, of which the following is a specification.

My invention relates to improvements in bag frame brackets, such as are employed to connect the lock-side band, or hasp-side band, with their associated inlay bands. Brackets for this purpose have been used for many years and such use involves no specific or difficult problem in the manufacture of hand sewed traveling bags. But the ordinary bag frame bracket interferes with machine stitching operations and modern production requirements call for the use of sewing machines for stitching the bags to the frame covers and linings. This has led to the use in some cases of specially formed brackets having surfaces adapted to deflect the awl or needle of a sewing machine when it strikes a bracket, whereby the stitching operation may proceed without cessation.

The object of my invention is to provide means whereby inexpensive brackets may be formed by blanking out pieces of sheet metal and simultaneously punching out their central portions to form stitch receiving apertures flanked on both sides by narrow connecting members, the openings being sufficient in size to ensure stitching operations between the connecting members, and the form of the openings being such as to provide struts of maximum strength in proportion to their width along the stitching line, thereby making it possible to utilize struts which are sufficiently thin or narrow where they cross the stitching line to avoid catching or holding the tubular awl with which sewing machines are equipped for such purposes and which passes through the goods in advance of the needle.

In the drawings:

Figure 1 is a side view of a bag frame equipped with my improved brackets.

Figure 2 is a sectional view drawn on line 2—2 of Figure 1.

Figure 3 is a perspective view showing the fragments of a lock-side or hasp-side band and associated inlay with the covering

applied over one of the connecting brackets and stitched in position across the bracket.

Figure 4 is a sectional view on line 4—4 of Figure 3.

Like parts are identified by the same reference characters throughout the several views.

In Figure 1 a bag frame is illustrated which, in its general characteristics, conforms to ordinary practice,—the lock-side band 1, associated inlay band 2, hasp-side band 3, and associated inlay band 4 being of ordinary construction.

The lock-side band 1 and the hasp-side band 3 are, however, connected with their associated inlay bands 2 and 4 respectively, by brackets 5 substantially half-elbowed at 6 and 7 and provided with apertures 8 in the portion between the points 6 and 7. These apertures 8 are of a size or diameter to nearly sever the bracket along a line parallel to the connecting bands and substantially midway between them. The apertures are preferably circular in form so that they can be produced by an ordinary punch simultaneously with the operation of blanking out the bracket. This circular form of the aperture is also preferred for the reason that it allows the bracket to have a maximum strength consistent with the desired purpose of allowing unobstructed machine stitching across the bracket.

It will be observed that a bracket, apertured as above described forms substantially a duplex connection between the associated bands—i. e.—a connection composed of two arms, each of which progressively widens from its central portion toward the respective bands,—the portions *a*, *a'* and *b*, *b'* being of considerably greater width than the portions *c*, *c'*. Said portions *c*, *c'* cross the stitching line and they are too narrow to materially obstruct the awl of the sewing machine. If struck by the awl, the latter vibrates sufficiently to dislodge and pass on one side or the other of the portions *c*, *c'* which it strikes.

The openings 8 have a greater diameter along the line of stitching than the distance between two successive operations of the needle, the diameter being sufficient to allow two stitching operations to take place be-

tween the two connecting arms of the bracket—i. e.—between the portions c , c' of the bracket.

With the above described bracket construction, each connecting arm of each bracket has its portion c or c' virtually embraced or surrounded by the covering material, which is held firmly to it by stitches on each side in close proximity thereto.

- 10 This not only re-enforces the bracket and prevents the thin arms c , c' from being distorted or bent out of place, but it also allows the covering to be held as firmly and smoothly in position over the brackets as in any 15 other portion. In fact, the connection of the covering is stronger at the brackets than at any other points along the line of stitching because of the plurality of transverse metallic arms comprising the portions c , c' 20 on the bracket.

The end portions of the bracket being in substantially half-elbowed connection with the central portion, it is obvious that the inlay bands will be outwardly offset from the 25 lock-side and hasp-side bands respectively. The needle of the sewing machine operates substantially perpendicularly to the central portions of the brackets.

I claim:

- 30 1. A connecting bracket for bag frame bands, comprising a piece of sheet metal having end portions in substantially half-elbowed relation to the central portion and having a central aperture of sufficient size 35 to nearly sever the central portion of the bracket leaving the end portions connected by two thin arms of insufficient width to obstruct the awl and needle of the sewing machine.
- 40 2. A bag frame bracket comprising a piece of stamped sheet metal having end portions adapted to be secured to the associated bands of the bag frame, and an intermediate portion provided with an aperture of sufficient size to nearly sever the end 45

portions of the bracket and also of a size to allow a plurality of stitching operations within the aperture.

3. In a bag frame, having lock-side and hasp-side bands, associated inlay bands, and covering material stitched thereto, the combination with said bands and covering, of connecting brackets having obliquely disposed central portions, arranged to support the inlay bands from their associated lock and hasp-side bands in an outwardly offset position, each of said brackets having its central portion provided with an aperture of a size to nearly sever the bracket at the points where they cross the stitching lines, each of said brackets being connected with the covering by a stitched thread passing through the aperture and through the material on both sides of the bracket.

4. In a device of the character described, a bracket adapted for attachment at its ends to bag frame elements and provided intermediate its ends with a portion lying substantially entirely in a given plane, said portion being provided with an aperture reaching almost to its margins, whereby the bracket portions intermediate such aperture and the margin of the bracket are so reduced in width as not to interfere materially with a stitching operation conducted transversely of the bracket and across said aperture.

5. In a device of the character described, a bracket having its end portions substantially at right angles to each other and having an intermediate diagonal portion lying substantially altogether in one plane, said intermediate portion being provided with an aperture extending almost to its margin, whereby to leave a very narrow rim adapted not to interfere materially with a stitching operation conducted transversely of said bracket.

AUGUST J. PETRIE.
